CLAIM

The ornamental design for a crop holder for a hydroponic system as shown and described.

DESCRIPTION

FIG. 1 is a front perspective view of a crop holder for a hydroponic systems;

FIG. 2 is a bottom perspective view of the crop holder for a hydroponic system;

FIG. 3 is a left elevation view of the crop holder for a hydroponic system;

FIG. 4 is a right elevation view of the crop holder for a hydroponic system;

FIG. 5 is a top plan view of the crop holder for a hydroponic system;

FIG. 6 is a bottom plan view of the crop holder for a hydroponic system;

FIG. 7 is a front elevation view of the crop holder for a hydroponic system;

FIG. 8 is a rear elevation view of the crop holder for a hydroponic system;

FIG. 9 is a top perspective view of the crop holder for a hydroponic system of FIG. 1 shown with environmental subject matter; and,

FIG. 10 is a top perspective view of the crop holder for a hydroponic system of FIG. 1 shown with environmental subject matter.

The portions of the crop holder for a hydroponic system shown in broken line form no part of the claimed design. The broken line showing of a channel in FIGS. 9 and 10 is for
